FINGER RING GUARD

Peter Grafstein, New York, N. Y.

Application June 19, 1948, Serial No. 147,088

Term of patent 3½ years

(Cl. D45—10)

To all whom it may concern:

Be it known that I, Peter Grafstein, a citizen of the United States, residing at New York, in the county of New York and State of New York, have invented a new, original, and ornamental Design for a Finger Ring Guard, of which the following is a specification, reference being had to the accompanying drawing, forming a part thereof.

In the drawing:

Fig. 1 is a perspective view of a finger ring guard, showing my new design;
Fig. 2 is a side elevational view;
Fig. 3 is sectional view taken on the line 3—3 of Fig. 1;
Fig. 4 is a top plan view; and
Fig. 5 is a bottom plan view of the same.

I claim:

The ornamental design for a finger ring guard, as shown.

PETER GRAFSTEIN.
